W. R. HILDEBRAND

RADIATOR

Filed May 7, 1921

Fig. 1.

UNITED STATES PATENT OFFICE.

WILLIAM R. HILDEBRAND, OF CHICAGO, ILLINOIS.

RADIATOR.

Application filed May 7, 1921. Serial No. 467,654.

My invention relates to heating and ventilating plants, and its objects are to effect economies in radiator construction, saving of space to be occupied by the heating and 5 ventilating radiator, a saving in the consumption of fuel, and to more effectually carry out the objects of my previous inventive efforts in this direction.

One particular object in the present improvement is to combine an alternate arrangement of steam and air spaces in such a manner that the latter will be accommodated in, substantially, the spaces heretofore found between the ordinary steam radiator sections whereby my present improvement will not take up any more room than said steam radiators, and whereby, also, the air to be heated and set in motion will be placed in more intimate contact with the 20 walls of the steam passages and thus be more rapidly heated thereby.

And with the above named objects in view my present invention consists of the novel construction, combination and arrangement 25 of parts hereinafter referred to in detail and more particularly pointed out in the appended claims.

Figure 1 is a perspective view of a radiator embodying my invention.

Figure 2 is an enlarged perspective view of one of the interior sections.

Figure 3 is an enlarged horizontal section through several broken away interior sections.

Figure 4 is a section taken substantially on the line 4—4 of Figure 2.

Figure 5 is a similar view of one of the end sections, taken substantially on the line 5—5 of Figure 2.

In the several views 2 and 3 are the end sections and these are similar to the intermediate sections with the exception that said end sections are closed by an outside wall 3'. An end section must also have a capacious air inlet. The intermediate sections of Figures 2, 3 and 4 are, respectively, designated by the numeral 4, and each is substantially alike at both sides. From the opposite outer side of each section's steam chamber projects a series of ribs or flanges 5, 6, 7 and 8, which, when placed against similar formations on adjoining sections, form an air-chamber. The flanges 5 and 6 are connected by a curved bottom flange 9 and a

top flange 10, the latter having cut away 55 portions or semi-bores 11, 12 and 13, which when placed opposite portions of an adjoining flange 10, form air outlets 14 that lead from air-spaces 15.

Each radiator section has the usual interior steam-space 16 with hubs 17 and 18, which when abutting adjoining hubs close the air-spaces to the steam spaces. The end section hubs 18 are connected with the source of steam supply by suitable and ordinary 65 fittings provided with a valve 19. The steam space 16 is bridged by a web or wall 20 with a slot 21 therethrough which places adjoining air spaces in communication with each other.

The radiator sections are clamped together by the usual bolt-rod 22, 23, and 24, and as a unit have their air-spaces provided with a capacious air-inlet, or mouth-piece, 25.

I claim as my invention—

1. A radiator composed of integral sections each having a hollow steam-space and interior and exterior projections adapted to be placed against similar projections on adjacent sections to form inclosed air-spaces, a steam-inlet and outlet common to all of the sections, an air-inlet common to all of said sections and a plurality of air-outlets for each of said sections.

2. A radiator composed of sections, each section having a steam-space and a pair of air-spaces to be closed by similar air-spaces on adjoining sections, means securing all of said sections together to form a radiator unit, a steam-inlet and an air-inlet common 85 to all of said sections, and a plurality of air-passages leading from the top of each of said air-spaces to the outer air.

3. The combination with a radiator composed of sections having hollow steam-space interiors open to each other, of a series of projecting ribs on the opposite sides of each section and adapted to abut against similar ribs on adjoining sections to form air-spaces, each of said air spaces having a plurality of air-outlet passages in the top of the radiator, channels through said steam-spaces which place said air-spaces in communication with each other, and an air-intake common to all of said air-spaces for each of said air-spaces.

In testimony whereof I have hereunto signed my name.

WILLIAM R. HILDEBRAND.
